UNITED STATES PATENT OFFICE.

ERNST TROIKE, OF SANDUSKY, OHIO.

ENGINE-MUFFLER.

990,686.

Specification of Letters Patent. Patented Apr. 25, 1911.

Application filed February 2, 1911. Serial No. 606,247.

To all whom it may concern:

Be it known that I, ERNST TROIKE, a citizen of the United States, residing at Sandusky, in the county of Erie and State of Ohio, have invented certain new and useful Improvements in Engine-Mufflers, of which the following is a specification:

This invention embodies improvements in that type of mufflers for explosive engines shown in my issued Letters Patent No. 950,215, dated February 22, 1910, and wherein the muffler described comprises an exhaust pipe surrounded by a plurality of cylinders forming concentric chambers into 15 which the exhaust gases are led, and from one of which they finally escape.

The object of the invention is to simplify the construction shown in my former patent, and to provide an end outlet for the muffler especially adapted to its use in connection 20 with marine and auto engines.

For a full understanding of the present invention, reference is to be had to the following description and to the accompanying drawings, in which—

Figure 1 is a longitudinal sectional view of a device embodying the invention; Fig. 2 is a transverse section taken on the line 2—2 of Fig. 1; Fig. 3 is a view taken on line 30 3—3 of Fig. 1; Fig. 4 is a modification showing a slightly different form of outlet head.

Throughout the following detail description, and on the several figures of the drawings, similar parts are referred to by like 35 reference characters.

In the drawings 4 denotes an exhaust pipe threaded at its opposite terminals. An outlet head 5 is connected with one end of the pipe 4 and the other end of said pipe 40 passes through an opening in an inlet head 7. A union 6 is screwed upon the last mentioned end of the pipe 4 and is connected with the exhaust pipe of the engine or motor. Between the heads 5 and 7 are arranged concentric cylinders 9 and 10 located in spaced 45 relation with respect to each other and the pipe 4. The heads 5 and 7 are provided with annular grooves 8 receiving the ends of the cylinders 9 and 10, and positioning the latter properly with respect to the heads.

At its end remote from the union 6, the pipe 4 has the apertures 12 and at the opposite end portion of the muffler, the cylinder 9 has the apertures 11.

The head 5 is of peculiar formation comprising an outermost annular flange directly

engaging the outer cylinder 10, and an inner supporting member 13 connected with the head by the lateral integral web 16 and the radial webs 15. The head 5 may be 60 molded so as to afford an integral construction and the supporting member 13 has a lateral boss 14 projecting therefrom and internally threaded to receive the threaded end of the pipe 4 adjacent thereto. The 65 outermost portion of the supporting member 13 has one of the grooves 8 before mentioned to receive the end of the cylinder 9.

In the operation of the muffler, the exhaust gases pass into the pipe 4 through the apertures 12 and 11 into the space between the cylinders 9 and 10. From the above space the exhaust gases pass between the radial webs 15 and the space between the supporting member 13 and the body of the 75 head 5, out of the muffler through a tubular outlet 17. In Fig. 4, the outlet 17 is threaded so that a pipe may be connected thereto to conduct the exhaust gases to any suitable point of escape. The union 6 not only affords a coupling between the pipe 4 and the exhaust pipe of the engine, but it constitutes a clamping member for forcing the head 7 against the ends of the cylinders 9 and 10, whereby the latter are effectively 85 clamped between the heads 5 and 7.

Having thus described the invention, what is claimed as new is:

1. In a muffler, in combination, a pair of heads, a pipe connected with one of said heads and passing through the other head, concentric cylinders surrounding said pipe and forming annular chambers or compartments, the pipe and innermost cylinder having apertures permitting the exhaust gases to pass from the pipe to the space between said cylinders, one of the heads having an outlet therein and being provided with a supporting member spaced therefrom on the inner side thereof and affording the above mentioned connection between the pipe and head, said supporting member closing the adjacent end of the pipe and the adjacent end of the inner cylinder, the head being formed with passages communicating with the interior of the outer cylinder and leading between the supporting member and head to the outlet of the latter.

2. In a muffler, in combination, an inlet head, an outlet head, a pipe extending between said heads and passing through the inlet head, concentric cylinders surrounding

2
said pipe, the outlet head having a supporting member integrally connected therewith but spaced from the inner side thereof, said supporting member being detachably connected with the adjacent end of the pipe aforesaid and closing said end of the pipe and the adjacent end of the inner cylinder, the outlet head having an outlet located adjacent to the supporting member above mentioned, a union screwed upon the end of the pipe adjacent to the inlet head and clamping the latter against the ends of the cylinder.

ders to hold the latter in proper position between the heads, the pipe and inner cylinders having apertures to permit the exhaust 15 gases to pass from the pipe to the space surrounded by the outer cylinder and thus out of the outlet aforesaid.

In testimony whereof I affix my signature in presence of two witnesses.

ERNST TROIKE.
